United States Patent Office.

ADAM McMULLEN AND JOHN H. ROCK, OF STERLING, ILLINOIS.

Letters Patent No. 77,508, dated May 5, 1868.

IMPROVEMENT IN HARNESS.

The Schedule referred to in these Letters Patent and making part of the same.

TO ALL WHOM IT MAY CONCERN:

Be it known that we, ADAM McMULLEN and JOHN H. ROCK, of Sterling, in the county of Whitesides, and in the State of Illinois, have invented certain new and useful Improvements in Closed Hames-Tug and Breast-Collar; and do hereby declare that the following is a full, clear, and exact description thereof, reference being had to the accompanying drawings, and to the letters of reference marked thereon.

In the annexed drawings, making part of this specification, A represents a breast-collar which is made closed in front, and which is padded in the usual manner. This collar is provided with the usual neck-straps G and J for supporting it. C represents a brace, which is made of sheet metal, and covered with leather. This brace has a hole through it at each end, by means of which it is riveted to the collar A.

B B represent hames-tugs, and D D neck-yoke tugs, which hames-tugs are provided internally with plates of metal, in which an eye is formed, through which they are riveted to the collar A. L and I represent large-headed rivets, which pass through the ends of the brace C, and through the tugs B and D, to confine them to the collar. These rivets make a very strong and permanent attachment, and at the same time act as pivots upon which the tugs turn to accommodate themselves to the motion of the whiffle-tree, or to its height, and also to the motion and height of the neck-yoke.

P P represent rings, which are secured in the forward ends of the tugs D D.

F represents a strap which lies in front of the collar A, and which connects the two rings P P. This strap F receives and supports the strap from the neck-yoke or the vehicle-pole.

H H represent straps which fasten at one end into the rings P P, and at their other ends into rings which are secured to that portion of the neck-strap marked G.

These straps H H support the neck-yoke pole, through tugs D and strap F, independently of the breast-yoke.

It will be seen that by means of the arrangement herein described, we are enabled to make light breast-strap harness answer for double teams as well as single, and that the tugs are enabled to accommodate themselves to the various movements of the whiffle-trees and neck-yoke or pole of the vehicle.

What we claim is—

The tugs B D, brace C, straps H and F, and collar A, when the various parts are connected together and operating in the manner as herein set forth.

In testimony that we claim the foregoing, we have hereunto set our hands, this 12th day of February, 1868.

ADAM McMULLEN,
JOHN H. ROCK.
